UNITED STATES PATENT OFFICE.

A. H. BLACK AND C. R. BLACK, OF INDIANAPOLIS, INDIANA.

HYGROMETER.

Specification of Letters Patent No. 31,773, dated March 26, 1861.

To all whom it may concern:

Be it known that we, A. H. BLACK and C. R. BLACK, both of Indianapolis, in the county of Marion and State of Indiana, have 5 invented a new and Improved Hygrometer, which we term "The Natural Weather-Guide;" and we do hereby declare that the following is a full, clear, and exact description of the same, reference being had to the 10 accompanying drawings, forming part of this specification, in which—

Figure 1 is a face view of the instrument. Fig. 2 is a central vertical section of the same. Fig. 3 is a side view representing the 15 operating portion of the instrument detached. Fig. 4 represents the seed and twisted awn of a grass of the order "stipa", such awn constituting the principal element of our instrument.

20 Similar letters of reference indicate corresponding parts in the several figures.

To enable others to make and use our invention we will proceed to describe its construction and operation.

25 A is a board or case upon or within which is the dial *a*, from the center of which there is a hole through the back of the board or box for the reception of a plug *b*, of wood or other material in the center of which is 30 inserted and secured one end of the twisted axis *c*, composed of a portion of the length of the awn represented in Fig. 4. The twisted axis has secured to it at or near its opposite end, which projects through an 35 opening in the center of the dial, the index *d*.

e, is a glass, covering the index and dial but having a hole in the center for the admission of the atmosphere around the axis *c*.

40 *f*, is a pointer, fitted to the hole in the center of the glass *e*, in such manner as not to obstruct the entrance of air through the said hole, and in such manner as to be capable of adjustment by hand outside the glass

for the purpose of showing what may have been the position of the index *d*, at a certain 45 time.

As the twisted axis *c*, twists and untwists itself with the changes in the hygrometric condition of the atmosphere, the index is caused to turn in one direction or the other, 50 and, by a proper system of graduation of the dial, may be made to indicate the degree of moisture in the atmosphere. If the twisted axis *c*, be of considerable length it will make more than a complete revolution between the 55 extremes of the hygrometric condition of the atmosphere, and in fact if nearly the whole awn be used for the axis it may make even three or four revolutions, and as these could not be traced upon the dial without 60 very constant watching, we propose to use in some cases the supplementary index *g*, which is made in the form of the letter *L*, as shown in Figs. 2 and 3, and secured to the twisted axis at a suitable point between 65 where it is secured in the plug *b*, and where the index *d*, is attached, and when this index is used the differential movement between it and the main index *d*, may be easily traced.

h, is a thermometer attached to the board 70 *A*, but constituting no part of our invention.

We do not claim broadly the idea of employing plants, for the purpose of obtaining hygrometric indications; but

Having thus described our invention, we 75 claim and desire to secure by Letters Patent as an improved article of manufacture—

A hygrometer which has its axis made of the order of grasses "stipa", with two or more indices thereto attached and otherwise 80 constructed as herein shown and described.

A. H. BLACK.
C. R. BLACK.
